Primary Examiner — Ian Simmons*Assistant Examiner* — Mark A Cavanna(74) *Attorney, Agent, or Firm* — Eric Krich; Krich & Associates(57) **CLAIM**

The ornamental design for an “educational projector device,” as shown and described.

DESCRIPTION

FIG. 1 is a perspective view of a educational projector device, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken line showing of sight words formed in a cap of the device, and a battery compartment in a bottom of the device, are included for the purpose of illustrating environmental structure and forms no part of the claimed design.
